UNITED STATES PATENT OFFICE.

JOHN M. JONES, OF PALMYRA, NEW YORK.

PRINTING-PRESS.

SPECIFICATION forming part of Letters Patent No. 379,958, dated March 27, 1888.

Application filed February 11, 1887. Serial No. 227,303. (No model.)

To all whom it may concern:

Be it known that I, JOHN M. JONES, of Palmyra, in the county of Wayne and State of New York, have invented certain new and 5 useful Improvements in Printing-Presses, of which the following is a specification.

My invention relates to printing-presses, and has reference more particularly to that class of presses in which the bed and platen both 10 move toward each other, although the improvements are applicable to other classes of presses.

In the drawings, Figure 1 is a side elevation of a press, showing my improvements applied thereto; Fig. 2, a vertical central section of the same; Fig. 3, a section on the line *xx* of Fig. 2; Fig. 4, a top plan view; Figs. 5 and 6, perspective views of the plates which 15 form the roller-bearings, and Figs. 7 and 8 views illustrating certain details.

A indicates a substantial framing, B the platen, and C the movable bed, all of which parts may be of usual construction, and in the framing A is driving-shaft D, which serves to 20 impart the necessary movements to the platen, bed, and inking-rollers.

In order to throw off or vary the impression I adopt the construction shown in Figs. 1, 4, and 8, upon reference to which figures 30 it will be seen that the shaft E, journaled in the side plates of bed C, is provided at its ends with eccentric journals *a*, to one of which is secured a radial arm, *b*. This arm is jointed at its outer end to an upright bar or 35 rod, *c*, or to sleeve *d* thereon, as shown in Figs. 1 and 8, said rod *c* being connected at its lower end with one arm, *e*, of an elbow-lever, *F*, pivoted upon a fixed stud projecting from the side of frame A, as indicated in Fig. 40 1. The other arm, *f*, of this elbow-lever extends upward alongside the frame, and at its upper end is fashioned into or provided with a handle, and passes through a loop or guide, *g*, secured to the frame, the loop or guide being provided at each end with a recess in its side wall, into which the handle may spring to retain the lever in any desired position. It 45 will be seen upon reference to Fig. 1 that as the elbow-lever *F* is rocked upon its pivot, 50 acting through the rod *c* and arm *b*, it rocks the shaft E in its bearings in the bed. As the pitman G, connecting the driving-shaft D with the shaft E, are journaled upon the eccentric portions of the latter, the throw of the pitmen

will be varied—that is, increased or diminished as shaft E is rotated in one or the other directions.

In order to vary the degree of rotation I provide the rod *c* with an adjustable sleeve, *d*, to which I pivotally connect the radial arm *b*. 55 Screwing into the upper end of rods *c* is a stem, *h*, which is provided at its upper end with a lateral flange, *i*, and enlarged head *j*, and near its lower end with a collar, *k*, as shown in Figs. 1 and 8. Sleeve *d* rests at its 60 lower end upon this collar, and as the stem *h* is screwed out of the rod *c* the sleeve rises with the stem. At its upper end the sleeve *d* is 65 advisably provided with a lateral flange to fit beneath and against the flange *i*, and on one 70 side of the sleeve there is formed a socket, *l*, in which is placed a pointed pin, *m*, which is urged upward by a spring, *n*, in the bottom of the socket. The pointed end of the pin *m* enters one or another of a series of concavities or 75 sockets, *o*, in the under face of the flange *i*, as shown in Fig. 8, and is held in engagement therewith by the spring *n*.

It will be seen that as the stem *h* is screwed 80 into or out of the rod *c* the distance between the points where the elbow-lever *F* and radial arm *b* connect with the rod *c* will be increased or diminished, and therefore the throw of the elbow-lever will be correspondingly changed.

Upon the side of the frame A, a little below 85 and to one side of the shaft H, I secure a bracket, *p*, (shown in Fig. 1,) which is adapted to receive horizontal arm *e* of the elbow-lever *F* when the upper end of the latter is thrown forward to throw the impression on. It will 90 be noticed that the pivot of elbow-lever *F* and the shaft H are in the same horizontal plane, and when the arm *e* of the elbow-lever *F* rests upon the bracket *p* the pivotal point of connection between the arm *e* and the rod *c* will 95 be directly opposite the shaft H, and from this construction it will be seen that as the bed C moves back and forth upon the shaft H the throw-off mechanism *a b c* will move bodily 100 with the bed C, as the center of motion of the throw-off mechanism will be opposite the shaft H.

In order that the inking-rollers may be prevented from passing back and forth over the form I employ adjustable roller-bearers or 105 guide-plates *I I*, and apply said plates or bearers to the sides of the movable bed, as shown in Figs. 1, 2, 3, and 4, arranging them in such

manner that when they are projected beyond the front edges of the bed-frame the journals or shafts of the inking-rollers will move over and upon the edges of said plates or bearers instead of over the front edges of the bed-frame. This adjustment will of course raise the inking-rollers so far away from the face of the bed as to prevent them from inking the form. When the bearers or plates are retracted, so that their edges will be in line with or in rear of the front edges of the bed-frame, the inking-rollers will then be allowed to move upon said front edges and ink the form. For the purpose of moving said plates I back and forth I employ the same operating lever that is employed for changing the impression, and it will be noticed that by this arrangement whenever the impression is thrown off the plates will be projected outward, so as to prevent the inking-rollers from touching the form.

Upon reference to Figs. 1, 2, 3, and 5 it will be noticed that the plates I I are provided near their front edges with guide-slots *r r*, to receive blocks or lugs *s s*, formed upon or secured to the side plates of the bed C. The plates I I are each provided with a slot, *t*, to receive a stud, *u*, on the side plates of the bed, and are further provided with a large guide-slot, *v*, which receives a boss or enlargement, *w*, formed upon the side plates of frame C, as shown in Fig. 3. The walls of the slots or openings *r r* and *t* are countersunk or beveled on their outer faces, as shown in Figs. 3 and 5, so that the blocks which work in said slots may serve not only to guide the plates, but also confine them to the bed-frame.

Upon the shaft E, just inside the sides of the bed-frame, are secured collars J, as shown in Figs. 2, 3, 4, and 7, each collar being provided with a rigid arm, K, bearing at its end an anti-friction roller, L. This roller, or, in case the roller be omitted, the arm K itself, works between two raised flanges, M and N, upon the inner face of each plate I, as shown in Figs. 2, 3, and 4.

When the upper end of hand-lever F is thrown forward to throw the impression on, the shaft E is rocked in such direction as to cause the arm K to rise, and in thus rising it strikes against the flange N on plate I, and, owing to the inclination of the said flange, this movement of the arm against the latter causes the plates to move back until their front edges are back of or on line with the sides of the bed-frame. When the hand-lever F is moved to the position shown in Fig. 1 to throw the impression off, the shaft E is rocked in the reverse direction—that is to say, it is rocked so as to throw the free end of the arm K downward. In thus moving downward the arm K strikes against the lower end or tail of the flange or lug M and causes the plates or bearers I I to project beyond the front edge of the bed-frame.

I do not claim, broadly, the application of movable plates or bearers to a press for the purpose of preventing the rollers from touch-

ing the form, as I am aware that such a device has been patented. As shown in Figs. 1, 2, and 4, the shaft E is provided with a lug or cam, *x*, about midway between its ends, and against this lug bears the lower end of an arm or lever, O, pivoted at a point between its ends to the ink-table framing or support. At its upper end the lever O is provided with an ink-fountain, P, of any suitable construction, and it will be seen that as the shaft E is rocked in its bearings, so as to throw the impression off and advance the plates or bearers I I, the lug *x* on the shaft will bear against and throw the lower end of lever O outward. This movement of the lever throws the ink-fountain P down in proper position to feed the ink to the ink-table or rollers. A spring, *y*, is connected with the lever O, so as to return the lever and its fountain P to their normal positions.

Q indicates one of the ink-roller carriages, which is mounted upon the shaft E, as is usual, and which is provided with spring-actuated rods R R, carrying at their upper ends blocks or bearings S S, in which the rollers are mounted.

Upon reference to Fig. 1 it will be noticed that the blocks or bearings S S are each provided with a loop, *z*, by which the rods or the blocks carried thereby may be raised to release the rollers.

T T indicate the gripper-arms, which are carried by a rod or shaft journaled in arms or lugs at the lower edge of the platen B, as shown in Figs. 1 and 2, and U indicates a downwardly-extending arm secured to the gripper rod or shaft and advisably provided with a friction-roller at its lower end. Upon the frame of the machine is a block, V, (shown in Figs. 1 and 4,) having a substantially-upright rear face, upon which face the lower end of the arm U travels, as the platen moves toward and away from the bed.

A spring, *a'*, connects the grippers or gripper-shaft with the platen in such manner as to exert a constant tendency to hold the grippers in an upright position. As the platen is rocked upon its shaft, the arm U on its roller rides down the upright face of block V, placing the spring *a'* under increasing tension or strain until the arm or roller reaches the lower face of the block. After the impression has been made the platen swings or oscillates backward upon the shaft and the arm U rides up the upright face of the block V. The spring *a'* and the bearing-faces of the block V are so arranged that when the platen reaches the limit of its backward movement, as in Fig. 1, the grippers will be substantially vertical. The block V and arm U prevent the spring *a'* from throwing the gripper too far toward the bed, and also cause the grippers to fall down upon the platen as the latter is rocked.

The feeding-table W is provided at one corner with a socket, X, which receives an arm, Y, secured to the right-hand feed-board, Z, as shown in Fig. 4. It will be noticed that the arm Y, instead of projecting outward over the

large gear-wheel in a longitudinal direction, curves downward, so that the feed-board Z may be placed outside of the gear-wheel and yet on the same level with the feed-table W, instead of above the same, as is customary.

Having thus described my invention, what I claim is—

1. In a printing-press, the combination, with a main frame, bed, and platen, of a shaft provided with eccentric end journals and mounted in the bed, a crank-shaft mounted in the frame, pitmen connecting the crank-shaft with the eccentric-journals of the bed-shaft, a hand-lever mounted upon the main frame, and adjustable connections between the hand-lever and the eccentric-journals, all substantially as shown, whereby the throw or rocking of the bed-shaft may be varied as desired.

2. In combination with frame A, platen B, and bed C, shafts D and E, mounted, respectively, in the frame and in the bed, pitmen G, connecting said shafts, an arm, b, secured to the end of shaft E, an elbow-lever, F, mounted upon the frame, and a rod, c, connecting the arm b and the elbow-lever, all substantially as shown, whereby when said lever F is rocked it rotates the shaft E in its bearings.

3. In combination with frame A, platen B, bed C, shafts D and E, and pitmen G, arranged and operating substantially as shown and described, a hand-lever, F, mounted upon the frame, an arm, b, secured to the end of shaft E, and an extensible rod, c, connecting the hand-lever F and arm b.

4. In combination with frame A, platen B, and shaft D, mounted in the frame, a bed, C, a shaft, H, mounted in the frame A, upon which the bed C rocks or oscillates, a shaft, E, mounted in the bed C, an arm, b, secured to said shaft E, a hand-lever, F, mounted upon the main frame, a rod, c, connecting the hand-lever with the arm b, and a bracket, p, secured to the main frame, substantially as shown, whereby when the lever f is thrown forward to throw the impression on, the arm e of said lever will rest upon the bracket p, as and for the purpose set forth.

5. In combination with frame A, platen B, bed C, and shaft E, mounted and arranged substantially as shown, hand-lever F, radial arm b, connecting-rod c, and an adjustable sleeve, d, mounted upon rod c and connected with arm b.

6. In combination with frame A, platen B, bed C, and shaft E, mounted and arranged to operate substantially as shown, hand-lever F, arm b, connecting-rod c, threaded at its upper end, a stem, h, screwing into rod c, and provided with a notched flange, i, a sleeve, d, connected with arm b, carried by the stem h, and provided with a spring locking device, m n, to engage with the screw-stem h, as and for the purpose set forth.

7. In a printing-press, the combination, with the bed C, of the rotatable shaft E, mounted in fixed bearings thereon, plates or bearers I, applied to the side faces of the bed,

an arm near each end of the shaft engaging with the plates or bearers, and mechanism for rocking or rotating the shaft E, all substantially as shown.

8. In a printing-press, the combination, with the bed C, of the rotatable shaft E, mounted therein, bearers or guides I I, applied to the side faces of the bed, and provided with flanges M and N, arms K K, secured upon the shaft and working against the flanges M N, and devices for rocking or rotating the shaft.

9. In a printing-press, the combination, with bed C and rotatable shaft E, provided with arms K K, and mechanism for rocking the shaft, of plates I I, applied to the sides of the bed and provided with slots r r, and blocks s s, secured to the bed and projecting into the slots, all substantially as shown.

10. In combination with the bed and the shaft E and its arms K K, the plates I I, each provided with countersunk slots r r and flanges M and N, and blocks s s, secured to the bed and working in the slots r r, substantially as shown and described.

11. In a printing-press, the combination, with a frame, A, platen B, and bed C, of adjustable roller-bearers applied to the bed C, an ink-supplying device or fountain, a lever mounted upon the frame, and connections, substantially such as shown, between the said devices and the lever, for simultaneously actuating said mechanisms.

12. In a printing-press, the combination, with a frame, A, platen B, and bed C, of adjustable roller-bearers, an impression-throw-off mechanism, an ink-supplying device or fountain, and a lever connected with and serving to actuate all of said mechanisms, substantially in the manner shown.

13. In a printing-press, the combination, with the frame, platen, and bed, of the roller-bearers applied to the bed, a shaft journaled in fixed bearings in the bed, and a lever for rocking said shaft and moving the roller-bearers, substantially as and for the purpose set forth.

14. In a printing-press, the combination, with the inking disk or plate R, of an inking-fountain, P, pivoted at a point below the ink-disk and extending upward over the upper edge thereof, a rock-shaft provided with a lug or eccentric, x, a hand-lever, and connections, substantially as shown, between the hand-lever and the rock-shaft, whereby, as the shaft is rocked, the lug or eccentric x thereon will serve to rock or tip the pivoted ink-fountain.

15. The combination, with pivoted lever O and ink-fountain P, of the shaft E, provided with lug or eccentric x, a spring, y, and means for rocking the shaft E.

JOHN M. JONES.
